(57) **CLAIM**

The ornamental design for an instrument, as shown and described.

DESCRIPTION

FIG. 1 is a perspective view taken from a top, front, left side of the instrument;

FIG. 2 is a front view thereof;

FIG. 3 is a right side elevation view thereof;

FIG. 4 is a left side elevation view thereof;

FIG. 5 is a top view thereof;

FIG. 6 is a back view thereof; and,

FIG. 7 is a bottom view thereof.

Throughout the Figures, the dash-dotted lines represent the bounds of the claim, and all other broken lines illustrate unclaimed portions of the instrument. None of the broken lines form a part of the claimed design.
